ADOLF MÜLLER-DEUTSCHMANN AND DETLEF STRÖH, OF ELTVILLE-ON-THE-RHINE,
GERMANY.

BREECH-ACTION FOR FIREARMS.

1,089,780.

Specification of Letters Patent. Patented Mar. 10, 1914.

Application filed December 4, 1911. Serial No. 663,912.

To all whom it may concern:

Be it known that we, ADOLF MÜLLER-DEUTSCHMANN, a subject of the King of Saxony, Germany, and DETLEF STRÖH, a subject of the German Emperor, and both residing at Eltvile-on-the-Rhine, Germany, have invented certain new and useful Improved Breech-Actions for Firearms, of which the following is a specification.

10 The present invention relates to a breech-action for automatic fire arms and consists in the provision of a piston interposed between the breech bolt and its closing spring so that, by means of a liquid introduced between the bolt and the piston the movement of the former can be transmitted to the latter.

In the accompanying drawings the invention is illustrated by way of example, Figure 20 1 representing a longitudinal central sectional view of the lock portion of a gun, and Fig. 2 a cross-section on the line A—B of Fig. 1.

The breech bolt *a*, which contains the firing pin and its actuating spring, is slidably arranged in the breech casing *d*. This casing is double-walled and holds the breech bolt piston-like within the space inclosed by the inner wall. In the space between the 25 walls a ring-shaped piston *b* is arranged which is actuated by a spring *c*. The spaces communicate with one another at the rear so that by means of a liquid, for instance glycerin, introduced into the inner casing *d* between the bolt *a* and the piston *b*, the movement of the bolt can be communicated to the spring *c*.

The casing *d* is formed with a guide block *e* by means of which it is slidably held in the 40 gun frame. A notch *f* in said block is normally engaged by a pivoted latch *h* which holds it in position. The latch is actuated by a spring *g* and is fitted at opposite sides of the gun with cheeks *i* by means of which it can be disengaged from the casing. When the latch is thus disengaged, the casing can be removed together with the breech bolt so as to enable the barrel to be cleaned.

Suitable gripping surfaces are provided at 50 the sides of the casing. The front end of the casing *d* joins at *x*—*x* a casing *k* which

at the opposite end holds the barrel. For loading the barrel, the breech bolt *a* is retracted by means of a plate *n* which slides on the casing *d* and which has its front end connected to the bolt. This plate forms a dust-proof closure of the ejecting aperture.

We claim:

1. In a breech action for automatic fire arms, the combination with a double-walled breech casing whose chambers communicate with each other in the rear, a slideable breech bolt in the inner chamber of said casing, and a spring in the outer chamber for holding said bolt in closed position, of a piston arranged in the outer chamber between the bolt and the spring so that, by means of a liquid introduced between the bolt and the piston, the movement of the former can be communicated to the latter, substantially as set forth.

2. In a breech action for automatic fire arms, a double-walled breech casing, a breech bolt fitted piston-like within the space inclosed by the inner wall of said casing, and a ring-shaped spring-actuated piston in the space between the walls, the spaces being in communication at the rear of the piston so that the movement of the bolt can be transmitted by means of a liquid to the piston, substantially as set forth.

3. In a breech action for automatic fire arms, a double-walled breech casing slidably fitted by means of a guide block in the gun frame so that it can be removed, a spring-actuated latch pivoted to the gun frame and adapted to engage a notch in the casing for securing the latter in position, a breech bolt fitted piston-like within the space inclosed by the inner wall of said casing, and a ring-shaped spring-actuated piston in the space within the walls, the spaces being in communication at the rear of the piston so that the movements of the bolt can be transmitted by means of a liquid to the piston, substantially as set forth.

ADOLF MÜLLER-DEUTSCHMANN.
DETLEF STRÖH.
